CLAIM

The ornamental design for a pallet for the handling of goods, as shown and described.

DESCRIPTION

The patent or application file contains at least one drawing executed in color. Copies of this patent or patent application publication with color drawing(s) will be provided by the Office upon request and payment of the necessary fee.

1.-2. Pallet for the handling of goods

FIG. 1.1 is a top plan view of the first embodiment of a pallet for the handling of goods, showing our new design;

FIG. 1.2 is a side elevation view thereof;

FIG. 1.3 is a another side elevation view thereof;

FIG. 1.4 is a bottom plan view thereof;

FIG. 1.5 is perspective view thereof;

FIG. 1.6 is another perspective view thereof;

FIG. 2.1 is a top plan view of the second embodiment of a pallet for the handling of goods, showing our new design;

FIG. 2.2 is a side elevation view thereof;

FIG. 2.3 is a another side elevation view thereof;

FIG. 2.4 is a bottom plan view thereof;

FIG. 2.5 is perspective view thereof;

FIG. 2.6 is another perspective view thereof.

The red color lines in the reproductions are not part of the claimed designs.
